(57) **CLAIM**

The ornamental design for a laser impingement cooler, substantially as shown and described.

DESCRIPTION

FIG. 1 is a perspective view of a laser impingement cooler incorporating the design and depicting optional electrode contacts in broken lines;

FIG. 2 is a front view of the embodiment of FIG. 1;

FIG. 3 is a back view of the embodiment of FIG. 1;

FIG. 4 is a left-side elevation view of the embodiment of FIG. 1;

FIG. 5 is a right-side elevation view of the embodiment of FIG. 1;

FIG. 6 is a top view of the embodiment of FIG. 1;

FIG. 7 is a bottom view of the embodiment of FIG. 1;

FIG. 8 is a perspective view of a laser impingement cooler incorporating the design and omitting the optional electrode contacts depicted in FIG. 1 for clarity of disclosure;

FIG. 9 is a front view of the embodiment of FIG. 8;

FIG. 10 is a back view of the embodiment of FIG. 8;

FIG. 11 is a left-side elevation view of the embodiment of FIG. 8;

FIG. 12 is a right-side elevation view of the embodiment of FIG. 8;

FIG. 13 is a top view of the embodiment of FIG. 8; and,

FIG. 14 is a bottom view of the embodiment of FIG. 8.

The broken lines in the drawings depict portions of the laser impingement cooler that form no part of the claimed design.
